UNITED STATES PATENT OFFICE.

MORRIS WUERPEL, OF ST. LOUIS, MISSOURI, ASSIGNOR TO WESTINGHOUSE AUTOMATIC AIR & STEAM COUPLER COMPANY, OF ST. LOUIS, MISSOURI, A CORPORATION OF ILLINOIS.

AUTOMATIC CAR-COUPLING.

1,131,194.

Specification of Letters Patent. Patented Mar. 9, 1915.

Application filed October 18, 1907. Serial No. 397,601.

To all whom it may concern:

Be it known that I, MORRIS WUERPEL, a citizen of the United States, residing at St. Louis, in the State of Missouri, have invented new and useful Improvements in Automatic Car-Couplers, of which the following is a specification.

The invention relates to automatic car couplers, and more particularly to certain improvements on the car coupler shown in my prior pending application, Serial No. 368,694, filed April 17, 1907.

The car coupler therein described is of the type known as "radial draw bar coupler," and comprises a coupler head having a recess or chamber containing a pivotally mounted knuckle. The knuckle is provided with an offset locking face adapted to engage a corresponding face of a co-acting knuckle in a companion coupler head, and the knuckle is also provided with a rear curved face adapted to engage a curved lateral face of the recess of a companion head and thereby guide the knuckles into locking engagement as they approach the coupled position, means being provided to lock the knuckles when in coupled position. With a construction of this character, it has been found that the heads are sometimes liable to uncouple, should unusual or severe side or lateral strains occur.

It is therefore the principal object of my invention to provide means for preventing side or lateral movement of the coupler heads when in the coupled position.

In the accompanying drawing, Figure 1 is an elevational view of the improved automatic car coupler, shown in the coupled position; Fig. 2 a central sectional view thereof; Fig. 3 an end view of one of the coupler heads; Fig. 4 a central sectional view of one coupler head showing a slightly modified construction, and Fig. 5 an end view of the same.

The coupler, so far as it is similar to the construction shown in the above mentioned application, comprises a coupler head 1, having a recess or chamber 2, containing a piv-

oted knuckle 3, having an offset engaging face 6 and a rear curved face 4, adapted to engage the curved inner face 5 of the recess, as two heads approach, and thereby cause the corresponding surfaces 6 of the knuckles 3 to engage. The knuckles are then locked in position by the locking pins 7, which are adapted to drop between a rear face 10 of the knuckle and the curved face 5 of the recess in the head.

According to the construction shown in Figs. 1 to 3 inclusive, to prevent lateral movement of the heads, I provide central projecting flanges 8 on one side, and outer guide flanges 9, on the other side, and the flange 8 may be tapered outwardly, so that as the heads approach, the flanges 8 are guided into position between the flanges 9, and when in coupled position lateral movement is then prevented by the flanges 8. The flanges 8 may also be flared, so as to assist in gathering or centering the parts, as they come together.

The coupler may be constructed as shown in Figs. 4 to 5, in which the outer flanges are dispensed with, and a single flange 12 on one side of the head is adapted to engage the companion head and prevent side movement similar to the first described construction.

Having now described my invention what I claim as new and desire to secure by Letters Patent is:—

A coupler head comprising a casting having guide members and a central rigid lateral projection adapted to engage the guide members of a counterpart coupling head in the act of coupling, a shoulder formed in said projection, and a flange on the casting for engaging the shoulder of the counterpart coupling in the coupled position, to prevent lateral movement.

In testimony whereof I have hereunto set my hand.

MORRIS WUERPEL.
